UNITED STATES PATENT OFFICE.

JACOB M. WINTROB, OF PHILADELPHIA, PENNSYLVANIA.

DESIGN FOR A CABINET FOR SOUND RECORDING AND REPRODUCING MACHINES AND THE LIKE.

44,624.

Specification for Design.

Patented Sept. 2, 1913.

Application filed June 28, 1913. Serial No. 776,445. Term of patent 14 years.

To all whom it may concern:

Be it known that I, JACOB M. WINTROB, a citizen of the United States, and a resident of city and county of Philadelphia, State of Pennsylvania, have invented a new, original, and ornamental Design for Cabinets for Sound Recording and Reproducing Machines and the Like, of which the following is a specification, reference being had to the accompanying drawing, forming part thereof.

The figure is a perspective view of a cabi-

net for sound recording and reproducing machines and the like, showing my new design.

I claim:

The ornamental design for a cabinet for sound recording and reproducing machines and the like, as shown.

JACOB M. WINTROB.
